(57) **CLAIM**

The ornamental design for an advertising device, as shown and described.

DESCRIPTION

FIG. 1 is a perspective view of one embodiment of the present invention.

FIG. 2 is another perspective view of the embodiment shown in FIG. 1.

FIG. 3 is a front elevational view of the embodiment shown in FIG. 1.

FIG. 4 is a side elevational view of the embodiment shown in FIG. 1.

FIG. 5 is a top elevational view of the embodiment shown in FIG. 1.

FIG. 6 is a back elevational view of the embodiment shown in FIG. 1.

FIG. 7 is a bottom elevational view of the embodiment shown in FIG. 1; and,

FIG. 8 is a perspective view of another embodiment of the present invention.

The broken lines showing environment in the drawings are for illustrative purposes only and form no part of the claimed design.
